DESIGN FOR A TORCH BODY

David M. Hasbrouck, Jersey City, N. J., assignor
to Air Reduction Company, Incorporated, New
York, N. Y., a corporation of New York

Application October 17, 1934, Serial No. 53,651

Term of patent 14 years

To all whom it may concern:

Be it known that I, David M. Hasbrouck, a citizen of the United States, residing at Jersey City, in the county of Hudson and State of New Jersey, have invented a new, original, and ornamental Design for a Torch Body, of which the following is a specification, reference being had to the accompanying drawing, forming part thereof.

In the said drawing:

Figure 1 is an elevation of a torch body showing my new design.

Fig. 2 is a peripheral profile view of the main portion of the torch body.

Fig. 3 is a development of a zone of the portion of the torch body which is studded with plateaus in accordance with the dominant feature of the design.

I claim:

The ornamental design for a torch body, substantially as shown and described.

DAVID M. HASBROUCK.
